FLUSH TOP RIDER CHAIN FOR FLOOR CONVEYERS

Edward Mullen and Paul Klamp, Detroit, Mich.,
assignors to Mechanical Handling Systems, Inc.,
Detroit, Mich., a corporation of Michigan

Application March 23, 1950, Serial No. 151,422

6 Claims. (Cl. 198—170)

1

This invention relates to a floor type conveyor chain wherein tension links are integrally formed to ride along the upper surface of laterally spaced members of a chain track and to cover the central opening between such members. It has for its principal object to adapt the "Keystone" or "rivetless" type of chain, widely used in the conveyor industry, to provide desired self-supporting and covering characteristics while at the same time incorporating vertical flexibility and economy of manufacture through the use of "rivetless" chain constructional features.

In a prior application, Serial No. 7,316, a floor type conveyor chain of the roller type is disclosed wherein upper side links are adapted to span and completely cover a floor chain track and wherein center rollers on vertical axes are adapted to bear laterally against either side of the track and to provide anti-friction bearings in passing around horizontal curves in the conveyor track. Such construction, while highly effective for some applications, is subject to certain limitations including a lack of vertical flexibility such as may be required if the conveyor is required to travel up inclined slopes, e. g., in moving from one floor to another or in moving up any inclined ramp to reach a new level. Furthermore, such prior floor chain is relatively expensive as compared to the widely used rivetless construction. This latter consideration is a particularly significant factor when the chain is required to travel only along straight line reaches, other than in passing around drive and idler sprockets, and therefore realizes no appreciable benefit from the antifriction rollers.

Accordingly, it is the principal object of the present invention to modify the common rivetless chain construction in a manner adapting it for a floor chain use.

Another object is to provide such chain with track spanning, covering and flush top characteristics.

Another object is to adapt such chain to provide a substantial degree of vertical flexibility.

Another object is to provide a special construction for the uppermost side bar of the rivetless chain adapted to slide on a floor track and provide flush and covering characteristics.

Another object is to provide a special center link construction for such rivetless chain which includes a central extension to the uppermost surface of the chain adapted to span and ride on the top surface of the track and to cover the intermediate space between arcuate ends of adjacent upper side bars.

2

Another object is to incorporate appropriate clearance between such center link extension and the ends of adjacent side bars, as well as in the other components of the chain to accommodate substantial vertical flexure.

These and other objects will be more apparent from the following detailed description of a particular embodiment and from an examination of the drawings forming a part of the present application, wherein

Fig. 1 is a plan view of the assembled chain and track;

Fig. 2 is a side elevation partly in section of the assembled chain and track;

Fig. 3 is a sectional view through the chain and track taken along the line 3—3 of Fig. 2; and

Fig. 4 is a plan view of the special center link employed in such chain.

Referring to Figs. 1-3, it will be seen that a "chain-on-edge" position is employed. The chain is comprised of lower side bar elements 10, upper side bar elements 11, center links 12, headed locking pins 13, retaining caps 14 and nuts 15.

The lower side bar element 10 is of conventional rivetless chain construction having transverse recesses 16 adapted to receive either the headed end of the locking pin 13 or a retaining cap such as 14.

The upper side bar element 11 is especially constructed with a laterally extending flange 17 having semi-circular ends 18 and a width sufficient to span the center opening between opposed channel track members 19. The upper surface of the flange 17 lies in a single substantially continuous flat plane broken only by rectangular recesses 20, which extend down to horizontal seats 21, each adapted to receive the rectangular head of a locking pin 13. These links

are forged with continuous depending strengthening webs 22 extending longitudinally between open socket portions 23, each having a cylindrical opening 24 adapted to pass the cylindrical shank 25 of a locking pin 13.

The special center link 12 is adapted to be manufactured as a forging and is provided with ends closely resembling those of a standard rivetless center link, having semi-cylindrical surfaces for engaging the central portion of the cylindrical shanks of the locking pins 13. However, the central portion of the center link departs from conventional center link construction in that the side walls of the link are each provided with integral upward extensions 26, which connect with a cross-bridge portion 27 adapted to

span the channel members 19 of the track and having arcuate recesses 28 conforming generally to the semi-cylindrical ends 18 of the upper side bars 11. This bridge portion of the center link has an upper surface 17 of the side bars 11 in order to provide a substantially continuous flush top cover for the entire chain track. However, referring to Figs. 1 and 2, a sufficient clearance 29 is provided between the ends of the side bars 11 and the bridge portion 27 of the center link, as well as between the center links and side bars where they engage the locking pin 13, as shown at 30 and 31, to accommodate a limited articulation of the chain links in a vertical longitudinal plane.

The chain assembly is adapted to incorporate pusher dogs 32 for receiving and trapping the drive pin of a floor truck or any other load which is desired to be propelled by the floor chain. Such pusher dogs are pivotally connected at 33 to laterally spaced trunnions 34 formed integrally with a base plate 35 connected to the top surface 17 of an upper side link 11 through the use of a special locking pin 13a having a threaded extension 36 adapted to pass through the base plate 35 and to be fastened thereto with nuts 37.

Thus it will be seen that the present chain provides a modified rivetless type of construction for use as a drag chain in a manner which meets each of the objects set forth above.

While a particular construction has been shown and described in detail, it will be understood that various changes in the component elements might be resorted to without departing from the scope of the present invention as defined in the following claims.

We claim:

1. In combination with a submerged floor chain track having opposed walls defining an opening for accommodating a conveyor chain and supporting surfaces on either side of said opening, a conveyor chain of the rivetless type having vertically spaced side bar links connected to an intermediate center link by a headed locking pin, all of the uppermost of said side bar links being provided with integral flanges adapted to ride on the supporting surfaces of said track, and all of the center links having upward extensions integrally joined to a bridge member adapted to span the opening between the chain supporting surfaces of said track.

2. In combination with a submerged floor chain track having opposed walls defining an opening for accommodating a conveyor chain and supporting surfaces on either side of said opening, a conveyor chain of the rivetless type having vertically spaced side bar links connected to an intermediate center link by a headed locking pin, all of the uppermost of said side bar links being provided with integral flanges adapted to ride on the supporting surfaces of said track, and all of the center links having upward extensions integrally joined to a bridge member adapted to span the opening between the chain supporting surfaces of said track, said upper side bar links being provided with semi-circular ends and said bridge portion of the center link being provided with arcuate recesses for accommodating said ends.

3. In combination with a submerged floor chain track having opposed walls defining an opening for accommodating a conveyor chain and supporting surfaces on either side of said opening, a conveyor chain of the rivetless type having vertically spaced side bar links connected

10 to an intermediate center link by a headed locking pin, all of the uppermost of said side bar links being provided with integral flanges adapted to ride on the supporting surfaces of said track, and all of the center links having upward extensions integrally joined to a bridge member adapted to span the opening between the chain supporting surfaces of said track, clearance being provided between the bridge portion of said center link and adjacent end portions of the upper side bar links and between the respective side bar elements and center link where engaged by said connecting pin to accommodate a substantial degree of chain flexibility in a vertical plane.

4. In combination with a submerged floor chain track having opposed walls for defining an opening and accommodating a conveyor chain and chain supporting surfaces on either side of said opening, a conveyor chain of the rivetless type having vertically spaced side bars connected at either end to a center link by a headed locking pin, all of the uppermost side bars being formed with integral flanges adapted to span said opening and ride on said chain supporting surfaces and all of said center links having upwardly extending portions integrally joined to a bridging portion adapted to extend between adjacent ends of upper side bar links, the upper surface of said upper side bar links and the upper surface of the bridging portion of said center links being constructed to lie in substantially the same plane and provide a flush upper surface for the chain.

5. A conveyor chain of the rivetless type, including upper and lower side bar links joined at each end to a center link by a headed connecting pin, characterized by all of the upper side bar links being formed with integral laterally spaced flanges substantially exceeding the width of the lower side bar links and all of the center links being integrally formed with upwardly extending portions and a bridging portion, said bridging portion being adapted to extend between adjacent ends of said side bar links.

6. A conveyor chain of the rivetless type, including upper and lower side bar links joined at each end to a center link by a headed connecting pin, characterized by all of the upper side bar links being formed with laterally spaced flanges substantially exceeding the width of the lower side bar links and all of the center links being formed with upwardly extending portions and a bridging portion, said bridging portion being adapted to extend between adjacent ends of said side bar links, said upper side bar ends and said bridging portion of said center links being formed with arcuate curves having centers at the pivotal connections and being provided with clearance adapted to accommodate a substantial degree of flexure in a plane passing through the axes of the connecting pins.
